Inventor:

Geo. E. Sharowith.

UNITED STATES PATENT OFFICE.

GEORGE E. CHENOWETH, OF BALTIMORE, MARYLAND.

IMPROVEMENT IN HARVESTERS.

Specification forming part of Letters Patent No. 23,077, dated March 1, 1859.

To all whom it may concern:

Be it known that I, GEORGE E. CHENOWETH, of Baltimore, in the State of Maryland, have invented certain Improvements in Harvesters; and I do hereby declare the following to be a correct description of the same, reference being had to the accompanying drawings, in which—

Figure 1 is a perspective view of a part of the frame of a harvester with my improvements attached. Fig. 2 is a separate view of the post or standard with the driver's seat attached, and Fig. 3 is similar view of the socket or step into which the lower end of the standard is received.

The same part is marked by the same letter wherever it occurs in the drawings.

My improvements relate to the construction of the raker's seat.

My invention consists in giving to the lower end of the standard or post to which the raker's seat is to be attached a polygonal form, and receiving the end thus formed in a step or socket of corresponding shape, so that the standard may occupy any one of a number of different positions in the step and be firmly held in all, the object being to relieve the raker by changing his position and bringing a new set of muscles into play.

In the drawings, A marks the frame of the machine; B, the tongue; C, the hooked lever; D, the ring-bolt; E, the fulcrum of lever C; F, the standard of raker's seat; G, the raker's seat; H, the breast and back rest; J, the driver's seat; K, the polygonal extremity of standard F; L, the polygonal socket or step; M, fulcrum of tongue; a, plate attached to driver's and raker's seats; b, slot in standard; c, nut.

The raker's seat G is attached to the standard F by means of the plate a, which slides on the face of F, and a screw-bolt passing through slot b in the standard, and fastened at the back by nut c. By means of the bolt and nut the height of the seat is varied at pleasure, and by removing the nut the raker's seat G can be taken off and the driver's seat J put in its

place and fastened in the same manner at the height required. This is to be done when the machine is used as a mower.

When an obstruction is met with that requires the forward end of the platform to be raised the lever C must be depressed, which will raise the rear end of the tongue and elevate the front of the platform. The tongue B has its fulcrum at M, and a slot in its end for the passage of bolt D, as shown.

In an operation so laborious as that of raking grain from the platform of a harvester, it is clear that an occasional change of position will be a great relief to the raker. In the drawings the step and standard are octagonal, which will admit of three or four changes of position without interfering with the efficient action of the raker. It is obvious, however, that a figure of a greater or less number of sides may be employed without affecting the principle of my invention, which consists in relieving the raker by changing the angle of his seat in relation to the platform from which the grain is to be raked, in the manner described.

When the raker's seat is attached to the standard the rest H is used as a breast-rest or the raker; but when the driver's seat J is attached the rest H becomes a back rest for the driver, as in Fig. 2.

Having thus fully described my invention, I wish it to be understood that I do not claim a rectangular four-sided step or standard, whether oblong or square, for such have been used before, though without any view to the object sought by my invention; but

What I claim is—

A polygonal step having more than four sides, in combination with a standard or post the lower end of which corresponds in figure with the interior of said step, as and for the purpose described.

In witness whereof I have hereunto set my hand this 17th day of January, A. D. 1859.

GEO. E. CHENOWETH.
